UNITED STATES PATENT OFFICE.

HENRY DREWS, OF OTTO, TEXAS.

CHOKER-ROD LATCH.

Application filed March 25, 1927. Serial No. 178,315.

This invention relates generally to choker rods of automobiles, particularly those of the Ford type, and has more particular reference to a means whereby the rod may be secured in predetermined extended position with the end of permitting the proper functioning of the automobile engine before the same has become properly warmed.

It is well known that in the operation of a Ford automobile, the choker rod is normally maintained in inactive position by a coil spring and in order to maintain the air inlet valve of the carburetor in closed or partially closed position, it is necessary for the operator to manually retain the choker rod in pulled out condition until the motor has become properly heated. It is therefore the primary object of this invention to provide means whereby the choker rod may be secured in predetermined extended position so as to enable the driver to pay attention to other duties necessary in the proper operation of an automobile, at least until the motor has become sufficiently warm to facilitate the proper functioning of the same with the air inlet valve of the carburetor in fully opened position.

One of the most important objects of the present invention is to provide a choker rod latch of this character that may be easily and inexpensively secured to the instrument board of an automobile, the same including means for positively engaging the usual thumb button of the choker rod at any predetermined outward position of the same with respect to the instrument board. The construction of this latch is further of such a nature as to permit the locking member per se to be readily thrown downwardly with respect to the choker rod button for releasing the same whereupon the carburetor air valve will be moved to fully open position by reason of the usual control spring therefor.

A further object is to provide a choker rod latch of this character that is extremely simple in construction and design and one that may be readily applied by the owner of the automobile.

With the foregoing and other objects in view as the nature of the invention will be better understood the same comprises the novel form, combination and arrangement of parts hereinafter more fully described, shown in the accompanying drawing and claimed.

In the drawing wherein like reference characters indicate corresponding parts throughout the several views:

Figure 1 is a fragmentary section through an automobile instrument board through which is extended a carburetor choke rod having the usual thumb button upon the inner end thereof and with which instrument board is associated my improved choker rod latch, the same being disclosed as actually in use for maintaining the rod in outwardly drawn position.

Figure 2 is a front elevation of the device as attached to the instrument board, and

Figure 3 is a detail longitudinal section taken substantially upon the line 3-3 of Figure 1.

Now having particular reference to the drawing, A indicates the instrument board of an automobile, particularly those of the Ford type through an opening B in which is loosely arranged the usual carburetor choker rod C provided at its inner end with the usual thumb button D. My invention per se consists of a metallic plate 5 of predetermined shape and design that is rigidly secured to the inner face of the instrument board A beneath the opening B therein by a bolt and nut connection 6. This plate is of such a design as not to detract from the appearance of the automobile instrument board, the side edges thereof merging together at the upper end of the plate, said side edges being formed with inwardly extending flanges 7-7 of such tapering formation as to space the upper end of the plate 5 from the instrument board A as clearly indicated in Figures 1 and 2. The upper end of this plate 5 is formed with an opening 8 slightly above the opening B and the instrument board A in order that the choker rod C which extends upwardly at an incline may loosely pass therethrough. Upon the outer face of this plate 5 is a pair of L-brackets 9-9 between the outwardly extending portions of which is pivotally secured as at 10 the inner end of a narrow plate-like lever 11, the ends of which are preferably rounded as indicated in Figure 1. The inner edge of this plate-like lever is formed with spaced teeth 12 that are formed to extend at a slight obtuse angle toward the outer end of the lever as clearly indicated in Figure 1.

Obviously as the choker rod C is drawn through the opening in the instrument board and plates 5 by pulling upon the button D

the choker valve of the engine carburetor, not shown, is operated. After the rod has been pulled outwardly to the predetermined position, the plate like lever is swung upwardly so as to cause the engagement of adjacent teeth 8 of the lever upon opposite sides of the plate like end of the button D, the same being held therein due to the binding action that will be occasioned between the 10 teeth and the button by reason of the slight angle of the teeth with respect to the transverse axis of the lever. When it is desired to permit the choker rod to move inwardly so that the choker valve will open, it will 15 only be necessary to swing the lever 11 downwardly so as to disengage the teeth 8 from the button D.

It will thus be seen that I have provided a highly novel, simple, and efficient choker rod latch that is well adapted for all the purposes heretofore designated; even though I have herein shown and described the invention as consisting of certain detail structural elements it is nevertheless to be understood that some changes may be made therein without affecting the spirit and scope of the appended claims.

Having thus described the invention, what I claim is:

30 1. In a latch for automobile choker rods wherein the operating end thereof is provided with a pull head, a lever pivoted to a

support beneath the headed end of the rod, and teeth formed upon the edge of the lever adjacent the head of the rod for receiving 35 said head when said lever is swung toward the same.

2. In a latch for automobile engine choker rods wherein the outer end of the same projects through the automobile instrument board wherein said outer ends are provided with pulling heads, a plate for attachment to the instrument board adjacent said rod and means pivotally associated with said plate for locking engagement with the head at 40 predetermined extended positions of the same with respect to the instrument board.

3. In a latch for automobile engine choker rods wherein the outer end of the same projects through the automobile instrument 50 board wherein said outer ends are provided with pulling heads, a plate for attachment to the instrument board adjacent said rod and means pivotally associated with said plate for locking engagement with the head at pre- 55 determined extended positions of the same with respect to the instrument board, said means consisting of a lever the edge of the same adjacent the choker rod head being provided with teeth between which the said 60 head is disposed.

In testimony whereof I affix my signature.

HENRY DREWS.
